UNITED STATES PATENT OFFICE.

CHARLES J. HERR, OF GARY, INDIANA.

GATE.

Application filed May 18, 1925. Serial No. 31,038.

The present invention relates to a gate and aims to provide a structure wherein the gate is slideable and rotatable on a post, and means are provided whereby the gate may be lifted 5 and when released will automatically turn about the post a predetermined distance.

An important object of the invention is to provide a gate structure of this nature which is easy to operate, and one which is 10 not liable to easily become out of order.

The structure of the invention is exceedingly simple and proves thoroughly reliable and efficient in its operation.

With the above and numerous other objects in view as will appear as the description proceeds, the invention resides in certain novel features of construction, and in the combination and arrangement of parts as will be hereinafter more fully described 20 and claimed.

In the drawing:—

Figure 1 is an elevation of the gate embodying the features of my invention.

Figure 2 is a fragmentary vertical longitudinal section through the post and a portion of the gate structure, and

Figure 3 is a horizontal detail section taken on the line 3—3 of Figure 2 looking downwardly.

Referring to the drawing in detail, it will be seen that 5 designates a vertically disposed tubular gate post which is provided adjacent its upper end with a pair of longitudinally extending slots 6 which are diametrically opposed to each other. A second pair of slots 7 are provided in the post below the slots 6 and are extended diagonally in opposite directions and are diametrically opposed to each other. A sleeve 8 is mounted 35 on the upper portion of the post 5 and a sleeve 9 is mounted on the lower portion thereof. A rectangularly shaped gate frame 10 is mounted on these sleeves 8 and 9. The sleeves 8 and 9 are braced in relation to each 40 other by rods 11 and rods 12 extend from the sleeve 8 to the lower corners of the frame 10.

The sleeve 8 is formed with an internal annular groove 13 which receives the ends of a pin 14 extending through the slots 6. 50 A link 15 is attached to the pin 14 and extends upwardly through the tubular post 5. A pair of chains 16 are fixed to the upper terminals of the link 15. A collar 17 is attached to the upper extremity of the post 5 55 and supports upwardly and outwardly disposed brackets 18 to the upper ends of which

are pivoted levers 19 having suitable depending handles 20 on the outer extremities thereof. The inner extremities of the levers are attached to the chains 16. By pulling 60 down upon the handles 20 it will be seen that the gate frame and the sleeves 8 and 9 may be raised.

A pin 22 extends through the slots 7 and is normally held in a position at the upper 65 ends thereof by means of a spring 23.

A plurality of cam fingers 24 depend from the sleeve 8 about the post 5 forming notches therebetween for receiving the extremities of the pin 22 and the weight of the gate 70 structure will compress the spring 23 so that the pin 22 is in the lower extremities of the slots 7. The fingers 24 are provided with cam edges 26 on like sides thereof.

In the present embodiment of the invention there are four of the cam fingers 24 spaced at regular intervals about the post 5. When the gate is lifted so that the pin 14 is in the upper extremities of the slot 6 as previously described, the weight of the gate 80 will be off of the pin 22 so that the spring 23 will lift the same upwardly and shift the position of this pin so that when the gate is lowered, two of the cam surfaces 26 85 will engage with the pin 22. As the gate further lowers, the pin 22 will be moved to the lower extremities of the slots 7, and then stop so that the continued lowering of the gate with the cam surfaces or edges 26 sliding along the pin 22 will cause the gate to 90 rotate a quarter turn.

The construction, operation, and advantages of the gate will now be apparent without a more detailed description thereof. I have disclosed the present embodiment of the invention merely by way of example and the same attains all of the features of advantage enumerated in the statement of the invention and the above description. It is apparent that numerous changes in the details of construction, in the combination and arrangement of parts may be resorted to without departing from the spirit or scope of the invention as hereinafter claimed or sacrificing any of its advantages. 95 100 105

Having thus described the invention, what I claim as new is:—

A gate structure, including, in combination, a tubular fence post provided with a pair of diagonal oppositely disposed cam 110 slots diametrically opposed to each other, a pin extending through the post and piercing

the slots, a spring mounted in the post and associated with the pin for normally holding it at the upper extremities of the cam slots, a gate including a sleeve slideable and rotatable on the post and having cam fingers engageable with the outer extremities of the pin, and means for raising the gate so that the pin may be raised by the spring and shifted to a position so as to engage other cam fingers as the gate is allowed to lower, so that said fingers cooperate with said pin for automatically turning the gate, said

means for raising the gate including a pin projecting through a pair of vertical slots provided in the post and terminating within 15 an annular groove provided in the sleeve, a link extending upwardly from the last mentioned pin, chains attached to the links, and levers pivoted on the upper end of the post and engaged with said links so that they may 20 be swung for raising the gate.

In testimony whereof I affix my signature.

CHARLES J. HERR.
